UNITED STATES PATENT OFFICE.

EDMUND MAJOR, OF TERRAVILLE, SOUTH DAKOTA.

GUIDE FOR STAMP-MILLS.

SPECIFICATION forming part of Letters Patent No. 499,130, dated June 6, 1893.

Application filed December 5, 1892. Serial No. 454,070. (No model.)

To all whom it may concern:

Be it known that I, EDMUND MAJOR, of Terraville, in the county of Lawrence and State of South Dakota, have invented a new and Improved Guide for Stamp-Mills, of which the following is a full, clear, and exact description.

The invention relates to improvements in guides for stamp mills such as are shown in the Letters Patent of the United States, No. 469,157, granted to me February 16, 1892, and in an application for Letters Patent of the United States, Serial No. 435,169, filed by me June 1, 1892, and allowed September 24, 1892. The object of the present invention is to provide certain new and useful improvements in stamp mill guides, whereby the bearing blocks are securely held in place and can be readily adjusted whenever desired on account of wear or other causes.

The invention consists of a keeper adapted to be fastened to the girt or rail, and formed at its rear with side flanges bearing against the front of the girt and adapted to receive the back of the bearing blocks.

Reference is to be had to the accompanying drawings, forming a part of this specification, in which similar letters of reference indicate corresponding parts in all the views.

Figure 1 is a plan view of the improvement with parts in section. Fig. 2 is a transverse section of the same on the line 2—2 of Fig. 1; and Fig. 3 is a sectional side elevation of one of the keepers, on the line 3—3 of Fig. 2.

The improved guide for stamp mills is provided with the usual girt or rail A secured by bolts or other means to the battery posts B of the stamp mill. On the front of the girt or rail A are formed vertical recesses C, into which fit ribs D projecting from the backs of the keepers E secured in place on the girt A by bolts F, passing transversely through the said girt, as plainly shown in the drawings. Each keeper E is formed in the shape of an open casing, the back E' of which is engaged by the bolts F, and their heads extend into the casing, as plainly shown in the drawings.

The sides E² of each keeper extend downward and are outwardly inclined, as shown in Fig. 3, and the top E³ and the bottom E⁴ of each

keeper connect the sides E² with the back E' so that the entire keeper is very strongly constructed.

On the rear of the sides E² of each keeper are formed sidewise extending flanges E⁵ 55 each having its front face beveled to receive the correspondingly-shaped rear side of the bearing block G fitting on the corresponding side E² of the keeper and against the said beveled front of the corresponding flange E⁵. 60

On the front ends of each side E² are formed short sidewise extending flanges E⁶, at or near the middle of which is formed a recess E⁷ engaged by a flange plate H extending a suitable distance beyond the short flanges E⁶, 65 as plainly shown in Fig. 1. Each flange plate H is secured in place on the respective keeper E by means of a bolt I held by suitable lugs or ribs E⁸ on the inside of the keeper and formed integral with the sides thereof, as will 70 be plainly understood by reference to the drawings. The inner face of each flange plate H is beveled to engage the corresponding beveled front side of the corresponding bearing block G so that the latter is engaged on 75 three sides by the keeper and at its inner semi-circular recess by the stem of the mill. It will be seen that by screwing up the respective bolt I for the corresponding flange plate H, the latter securely presses the bearing blocks held on opposite sides of the keeper in place thereon, and also presses the said bearing blocks in firm contact with the front beveled sides of the flanges E⁶.

The sides of the guide or bearing blocks are 85 beveled to correspond to the inclination of the sides of the keepers so that the guide or bearing blocks G are free to slide upward and out of contact with the keeper or can be held firmly in place by adjusting the flange bolt 90 I, as above described. When the guide or bearing blocks become worn by the vertical movement of the stamp stem, they may be adjusted to the stem by loosening the flange bolt, and placing a thin piece of wood or 95 other material between the keeper and guide block.

As shown in Fig. 1, the bevel on the front of the flange E⁵ corresponds with the bevel on the inner face of the flange plate H, so that 100

the latter and the corresponding flange E⁵ securely hold the block in a dovetail formed by the flange E⁵ and the flange plate.

Having thus fully described my invention, 5 I claim as new and desire to secure by Letters Patent—

1. A guide for stamp mills provided with a keeper adapted to be secured to the girt or rail, and provided with inclined sides, integral flanges extending from the rear ends of the said inclined sides, the front faces of the said side flanges being beveled, a bearing block fitted on the adjacent inclined sides and beveled flanges of the said keeper and a flange plate held removably on the front end 15 of the keeper and projecting over the front faces of the bearing blocks on each keeper, substantially as shown and described.

2. A guide for stamp mills comprising a keeper adapted to be fastened to the girt or rail and provided with integral flanges extending sidewise from the rear ends of the inclined sides of the keeper, the front faces of the said side flanges being beveled, a bearing block fitted on the adjacent inclined sides and beveled flanges of the said keeper and a flange plate held removably on the front end 20 of the keeper and projecting over the front faces of the bearing blocks on each keeper, substantially as shown and described.

EDMUND MAJOR.
